UNITED STATES PATENT OFFICE.

WILLIAM A. HENNESSEY, OF SPRINGFIELD, MASSACHUSETTS.

STEAM-BOILER.

SPECIFICATION forming part of Letters Patent No. 242,314, dated May 31, 1881.

Application filed January 27, 1881. (No model.)

To all whom it may concern:

Be it known that I, WILLIAM A. HENNESSEY, of Springfield, in the county of Hampden and State of Massachusetts, have invented certain new and useful Improvements in Steam-Boilers; and I do hereby declare that the following is a full, clear, and exact description of the invention, which will enable others skilled in the art to which it appertains to make and use the same, reference being had to the accompanying drawings, which form a part of this specification.

Figure 1 is a longitudinal vertical sectional view, and Fig. 2 is a vertical cross-section, of my improved boiler; and Fig. 3 is a horizontal sectional view.

Similar letters of reference indicate corresponding parts in all the figures.

This invention relates to steam-boilers; and it consists in certain improvements in the construction of the same, which will be hereinafter described, and particularly pointed out in the claim.

It is well known that in tubular boilers as at present constructed the flame and gases of combustion pass directly through the centrally-located tubes or flues, causing them to wear out in much less time than the outer ones, and correspondingly decreasing the efficiency of the boiler.

My invention has for its object to so construct the boiler as to equalize the draft through the flues to the greatest possible extent, thereby increasing the usefulness of the boiler and economizing fuel.

The construction of my improved boiler will be readily understood by reference to the accompanying drawings, in which—

A represents the cylindrical shell of the boiler, riveted to which is an auxiliary cylinder, B, projecting at the rear end, as shown at C. Of the flues or tubes about one-half of the entire number are located in the auxiliary shell

B, as represented by the letters D D. The remainder, E, of the flues are located in the main shell A, as shown. The front end of the boiler is formed with a chamber, F, as shown.

By reference to the drawings hereto annexed the operation and advantages of my invention will be readily understood.

The flame, gases, and products of combustion pass from the furnace under the boiler, back, as indicated by the arrow, through the outer flues, E, to the chamber F, from whence they pass through the flues D in shell B out to the chimney-flues.

It will be seen that the flames, &c., pass directly under and around the projecting end C of the center flues, the advantage of which will be readily seen, heat which is usually wasted being in this manner utilized.

I prefer in practice to make the boiler with such an arrangement of dampers that immediately on starting up the fire the draft may be sent under the boiler or through the outer tubes only, and from thence directly up through the chimney.

Having thus described my invention, I claim and desire to secure by Letters Patent of the United States—

In a flue and tubular steam-boiler, the combination of the outer cylinder, A, and inner cylinder, B, having its rear end projecting from said cylinder A, each cylinder being provided with fire-tubes and return smoke-chambers, all constructed and arranged to cause the products of combustion to first impinge on their outer surface and then through the tubes on their inner surface, as shown and described.

In testimony that I claim the foregoing as my own I have hereto affixed my signature in presence of two witnesses.

WILLIAM A. HENNESSEY.

Witnesses:

JAS. F. O'NEIL,
HARRY WILLIAMS.
